UNITED STATES PATENT OFFICE

2,459,011

AMUSEMENT GAME APPARATUS

Harry E. Williams, Chicago, Ill.

Application June 3, 1947, Serial No. 752,135

4 Claims. (Cl. 273—88)

1

This invention relates to certain new and useful improvements in amusement game apparatuses wherein there are employed a plurality of figures simulating baseball players and arranged with respect to each other so as to be projected into the path of a baseball diamond to simulate the running of the bases of said diamond.

The invention has for its principal object the provision of a construction of the character hereinafter described which will afford a maximum degree of pleasure and amusement during the operation of the game.

Another and equally important object of the invention resides in the provision of a plurality of figures having a common support for rotation through a path simulating a baseball diamond and so arranged whereby each figure is normally concealed to the rear of an opaque portion of the diamond until individually released for simulation of running about the bases provided by the diamond.

Another object of the invention resides in an assembly and arrangement of parts, easy of operation and economical of manufacture.

A further object of the invention is the provision of an arrangement for successively projecting figures simulating baseball players, into the path of an area simulating a baseball diamond, to simulate the accomplishment of a single, double, triple, or home run hit.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of a game apparatus having embodied therein my invention;

Fig. 2 is an elevational view of the baseball diamond embodied in my invention;

Fig. 3 is a fragmentary detail view of the figure-carrying structure embodied in the invention;

Fig. 4 is a fragmentary detail view of the structure illustrated in Fig. 3, but showing the figure projecting into base-running position;

Fig. 5 is a side elevational view of the figure-supporting and operating mechanism;

Fig. 6 is a perspective view taken substantially on line 6—6 of Fig. 5;

Fig. 7 is a sectional detail view taken substantially on line 7—7 of Fig. 5;

Fig. 8 is a fragmentary detail view of the figure-releasing mechanism illustrated in Fig. 7, but showing the parts thereof in different positions;

Fig. 9 is a fragmentary detail view similar to Fig. 8, but showing the figure in projected position;

Fig. 10 is a perspective view of the figure-carry-

2

ing and rotating mechanism illustrated in Fig. 4, as viewed from the right thereof;

Fig. 11 is a perspective view of the plurality of actuating discs embodied in the figure-carrying and rotating mechanism shown in Fig. 10, and showing the same in exploded relation with respect to each other;

Fig. 12 is a side edge view of the figure-carrying arm embodied in the invention;

10 Fig. 12—A is a suggested form of electric circuit for energizing the electrical operating units embodied in the invention;

Fig. 13 is a fragmentary sectional detail view taken substantially on line 13—13 of Fig. 5;

15 Fig. 14 is a fragmentary sectional detail view taken substantially on line 14—14 of Fig. 10;

Fig. 15 is a fragmentary perspective view of the figure latch releasing mechanism embodied in the invention.

20 The several objects of my invention are accomplished by the preferred form of construction illustrated in the accompanying drawings, and in which Fig. 1 illustrates an amusement game apparatus in which my invention is embodied. This game apparatus includes a cabinet 10 having an upright box structure 11 within which the mechanism to be described is adapted to be housed.

Within the cabinet 10 and beneath a transparent glass closure 12' is a playboard 13 having appearing thereon a picture simulating a baseball diamond 12. Balls are projected on this diamond in a manner well-known in the art and by means not embodying this present invention. This mechanism, however, includes an outlet open-

35 ing in the playboard 13 normally closed by a spring flap 14. As the balls are projected from beneath this flap 14 onto the playing field of the playboard 13, a suitable bat 15 is manipulated by means of a plunger 16 to project the balls toward the upper end of the playboard for entrance into one of several stalls 17, from whence the balls are adapted to roll over certain control switches (not shown) which control the operation of the mechanism to be presently described.

40 The upright cabinet 11 has a substantially rectangular panel member 18 provided with a transparent area 19 simulating the path 20 of a baseball diamond D providing "Firs," "Second," and "Third" bases, 21, 22, and 23, respectively, and "Home" plate 24. This diamond D provides a medial area 25 which is substantially opaque so that when figures 26 are in the position shown at C, they will be concealed from the view of the player.

45 This present invention relates to the mechanism for projecting the players 26 from concealed position to the rear of the opaque area 25, to a position within the path 20, together with means for rotating the figures to simulate the running of the bases. In this connection there is mounted

60

within the cabinet 11 to the rear of the panel 18 a mounting plate M (Fig. 5) which supports the mechanism for rotating and projecting the figures 26 upon the path 20 of the baseball diamond for reasons hereinbefore stated. This mechanism comprises a motor 27 connected in circuit with a suitable source of electric energy. The motor includes a gear 28 mounted on the armature shaft 29 of the motor and operatively meshing with an intermediate gear 30 mounted upon a shaft 31, which shaft 31 is provided with a pinion 32 operatively meshing with a driving gear 33 mounted upon a shaft 34.

This shaft 34 has one end portion journaled in a plate 35 supported from the frame 36 of a motor 27 by spacer blocks 37. The shaft 34 projects forwardly through the mounting plate M, and secured to this shaft 34 is a disc 38 having formed in the peripheral edge thereof radially disposed V-shaped notches 39 (Figs. 6 and 11). Mounted on this shaft 34 for limited free rotation with respect thereto and forwardly of the disc 38, is a disc assembly 40 comprising a bushing 41 mounted on the shaft 34 for limited independent rotation with respect thereto. This bushing 41 is carried by a disc 42 fixed thereto in any suitable manner and having formed in its periphery a plurality of radially disposed slots 43.

The bushing 41 has a reduced portion 44 which projects through an opening 45 formed in a disc 46. This disc 46 may be said to be floatingly mounted upon the reduced portion 44 for limited free rotation relative thereto. The bushing 41 has an outer reduced portion 47 adapted to project through an opening 48 and be secured to a disc 49.

The discs 38 and 42 are keyed together by means of a pin 50 projecting through an opening 51, the opening 51 being of a slightly greater diameter than the diameter of the pin 50 to permit the limited free rotation of the disc 42 upon the shaft 34. The discs 46 and 49 are likewise keyed together by a pin 52 adapted to project in an opening 53 formed in the disc 49, the opening 53 being of a slightly greater diameter than the pin 52 to permit the aforesaid limited independent rotation between the discs 46 and 49. The disc 49 is provided with a plurality of radially extending arms 54 each of which support for pivotal movement the figure 26 in a manner now to be described.

On each of these arms 54 is pivotally connected as at 55, a latch finger 56 carrying on one side a laterally extending pin 57 for reasons hereinafter more fully explained. This latch finger 56 provides a latch head 58 which is adapted to have latched engagement with an end portion 59 of an arm 60 pivoted adjacent the end portion 59 to the arm 54 as at 61. The arm 60 is yieldably held in latched engagement with a latch head 58 by means of a spring 62 having one end portion 63 connected to the arm 60, and the opposite end portion connected as at 64 to the latch finger 56. When the arm 60 is released from latched engagement with respect to the latch finger 56, it is limited in its pivotal movement by the action of the spring 62, by a stop 65.

The outer end portion 66 of the arm 60 has pivotally connected thereto as at 67 the figure 26, the pivotal connection between the arm 60 and the figure 26 being such that when the figure is projected, in a manner to be hereinafter set forth, in the path 20 it will by gravity remain in an upright position.

The pin 57 (Figs. 3 and 4) is adapted to engage

in a V-shaped notch 68 formed in an arm 69, of which there are several, provided by the disc 46 in radial relation with respect to each other. The arm 60 (Fig. 12) comprises an angled end portion 70 connected as at 71 in any suitable manner to an extension 72 carrying a stud 73 to which the end portion 63 of the spring 62 is connected. Opposite this stud 73 is a trip pin 74.

On the plate M (Fig. 15) is arranged a trip plate 75 which is adapted to be engaged by the pin 57 carried by the latch finger 56, whereby upon engagement of the pin 57 with the trip plate 75, the latch finger 56 will be pivoted in a direction to disengage the latch head 58 from the end portion 59 of the arm 60, whereby to permit the arm 60 to be pivoted under the action of the spring 62 in a direction to dispose the figure 26 into concealed position behind the opaque area 25 from a position within the path 20 of the baseball diamond.

The mechanism for projecting the figure 26 from concealed position behind the opaque area 25 to a position within the path 20, in its preferred form of construction includes (Figs. 5 and 13) a plate 76 extending laterally from the mounting plate M and from an arm 77, of which it is formed as a part. This arm 77 is pivotally connected as at 78 to the plate M and carries a connecting link 79 which operates in an opening 80 formed in the plate M (Fig. 10). This link 79 connects the arm 77 to the solenoid rod 81 of an electro-magnetic coil 82. The plate 76 has connected thereto one end portion of a spring 83, the opposite end portion of the spring 83 being connected to the trip plate 75 (Fig. 5).

The arrangement is such that each time that the electromagnetic coil 82 is energized, the arm 77 will be pivoted to bear down upon the pin 14, whereby to pivot the arm 60 against the action of the spring 62 to dispose the end 59 of the arm 60 in latched engagement with the latch head 58, whereupon upon such engagement and as long as the arm 60 is in this latched engagement, the figure 26 will be positioned in the path 20 in full view of the operator of the game.

Means is provided for simultaneously pivoting all figures 26 which are disposed in the path 20 to a position behind the opaque area 25 of the panel 18. This is accomplished by a trip finger 84 (Figs. 6, 10, 14) formed as an integral part of a plate 85 pivoted to the mounting plate M as at 86, the pivotal movement of which plate is under the action of a spring 87 having one end portion connected to the trip finger 84 as at 88, and an opposite end portion as at 89 to the mounting plate M.

This plate 85 carries a connecting link 90 operable in an opening 90' formed in the plate M. This connecting link 90 connects the plate 85 with the solenoid rod 91 of an electromagnetic coil 92 mounted in any convenient manner to the rear of the mounting plate M.

In connection with the game apparatus, there may be employed a suitable score circuit which may include a control switch S (Fig. 6) having a feather wire 93 which is adapted to be engaged by the angled portion 70 of the arm 60.

Within runways (not shown) located beneath the board 12 and which have communication with the stalls 17 for the reception of the balls from the stalls 17, are arranged ball switches 103, 104, 105 and 106 which are adapted to be engaged by balls traveling through these runways. These switches are arranged in the electric circuit in the manner diagrammatically illustrated in Fig.

12—A, and these switches 103, 104, 105, 106, may be termed "First base," "Second base," "Third base," and "Home run" control switches.

Adjacent these switches and adapted to be first engaged by the ball before the ball engages these switches are switches 103a, 104a, 105a, and 106a.

The circuit diagrammatically illustrated in Fig. 12—A is one of many circuit arrangements which may be employed. In the present instance, the "First base," "Second base," "Third base," and "Home run" switches 103, 104, 105, 106, respectively, each control a circuit control device 103b, 104b, 105b, and 106b, in the form of an electromagnetic coil. These coils in turn control switches 103c, 104c, 105c, and 106c in turn controlling the circuit to the motor 27. In this circuit are also interposed the electric coils 82 and 92.

For purposes of illustration I have shown this circuit controlled by a coin controlled switch 107, and for the purpose of illustration this coin controlled switch 107 includes a coin slide 102 and a suitable timing device 108 (diagrammatically illustrated and of a well-known construction) which times the duration of operation of the game.

Arranged on the armature shaft 34 of the motor 27 and insulated therefrom are commutators 103d, 104d, 105d, and 106d, each comprising an insulated disc F and a contact brush E adapted when not in contact with the insulation insert of the disc to contact the disc to complete a circuit to the electromagnetic devices 103b, 104b, 105b and 106b.

The device operates in the following manner:

As the operation is substantially the same when any one of the switches 103, 104, 105, 106 is closed, with the exception of the number of men projected from behind the opaque portion 25 into the path 20 and the period of duration of the operation of the motor 27, it is only necessary to describe the operation of the "First base" switch 103.

A ball rolling down the runway will first contact the switch 103a and set up a circuit to the coil 82 which when energized will pivot the arm 77 to bear the plate 76 against the pin 74, whereby to pivot the arm 60 to project the figure 26 from behind the opaque portion 25 into the path 20 with the end portion 59 of the arm 60 in latched engagement with the latch head 58. Continued rolling movement of the ball engages the switch 103 to set up a circuit to the coil 103b. When energized, this coil 103b will close switch 103c whereby to set up a circuit to the motor 27 which, when energized, rotates the projected figure along the path 20 to the "First base" position of the diamond.

As the motor initially rotates by the closing of the switch 103, the brush E of the commutator 103d will move into contact with the disc F, and this will shunt the circuit through the disc F to the coil 103b whereby to retain the switch 103c closed notwithstanding the opening of the switch 103 by the passing of the ball therefrom. The motor will continue to operate until the brush E of the disc F engages the next insulated portion carried by the disc F, whereupon the circuit to the coil 103b will be broken and the motor cease to operate.

For the purposes of illustrating the operation of the device, let it be assumed that the player has accomplished only a "one-base hit" and that the timing device 108 is now moving the arm 109

in a counterclockwise direction as viewed in Fig. 12—A, from contact with the contact plate 110 onto the contact plate 110'. When the arm 109 contacts the plate 110', circuit is set up in the coil 92 whereupon when this coil 92 is energized it will pivot the plate 85 in an anti-clockwise direction as viewed in Fig. 6, to position the arm 84 into the path of movement of the arms 69 of the disc 46. This takes place before the motor 27 has ceased to operate. As the arm 84 obstructs the rotation of the disc 46, the continued rotation of the disc 46 will cause the edge 68 of the V-shaped notches of the arms 69 to bear against the pin 57 whereby to release the latched engagement between the arm 60 and the latch head 58 whereupon the arm 60 or such arms as are in projected position will pivot to a position to the rear of the opaque area 25 under action of the spring 62.

If one of the figures 26 should be projected at the position opposite the "third base" 23 and the disc 49 is caused to rotate, by virtue of the closing of one of the switches 103, 104, 105, 106, the figure is moved to a position to the rear of the opaque area 25 by engagement of the pin 57 with the trip plate 75 whereupon the latch head may be pivoted to release the latched engagement of the end portion 59 with the arm 60 and permit the arm 60 to be pivoted under the action of the spring 62.

At the completion of each rotation of the shaft 34 with the disc assemblies thereon, it is desirable that the figures be in their respective positions as shown in Fig. 10. This is accomplished by engagement of an indexing finger 97 in the slot 43 of the disc 42. This indexing finger 97 is formed as an integral part of a plate 98 pivotally connected as at 99 to the mounting plate M and normally urged toward the disc by a spring 100.

The arrangement is such that as the finger 97 engages an adjacent slot 43, it will, by virtue of engagement of the tapered edges 101 of the notches 39 formed in the disc 38, rotate the disc 42 slightly in advance of the disc 38 whereby at all times to position the figures 26 in their proper starting positions. When the motor 27 is energized for rotation, an edge of the adjacent notch 39 will bear upon the indexing finger 97 and pivot this finger 97 to disengage the end thereof from the adjacent slot 43. Figures which are projected into the path 20 and as they move from "third" base in a direction toward "home plate," will be positioned to the rear of the opaque area 25 by virtue of the engagement of the pins 57 with the trip plate 75, which engagement between these pins and the plate 75 releases the arms 60 from latched engagement with the latch heads 58.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. A mechanism for releasably supporting a rotatable figure simulating a baseball player for movement along the path of a member simulating a baseball diamond having an opaque area, com-

prising a rotatable disc member, means for rotating said disc member, an arm having one end portion pivotally connected to said disc member, a figure pivotally supported at the opposite end portion of the arm, a latch member pivotally carried by the disc member and having a latch head adapted to engage the pivoted end portion of said arm, spring means for releasably holding said arm in latched engagement with said latch head with said figure projected in the path of said diamond, and means for releasably moving said arm to dispose the latch head from latched engagement with said arm to permit said arm to pivot under the action of said spring means from a position within said path to a position to the rear of said opaque area.

2. A mechanism for releasably supporting a rotatable figure simulating a baseball player for movement along the path of a member simulating a baseball diamond having an opaque area, comprising a rotatable disc member having a radially extending arm, means for rotating said disc member, an arm having one end portion pivotally connected to said radially extending arm, a figure pivotally supported at the opposite end portion of said second-named arm, a latch member pivotally carried by said radially extending arm and having a latch head adapted to engage the pivoted end portion of said second-named arm, spring means for releasably holding said second-named arm in latched engagement with said latch head with said figure projected in the path of said diamond, and means for releasably moving said second-named arm to dispose the latch head from latched engagement with said second-named arm to permit said arm to pivot under the action of said spring means from a position within said path to a position to the rear of said opaque area.

3. An apparatus of the class described comprising a rotatable shaft, a disc fixed to said shaft for rotation therewith, a disc assembly on said shaft adapted for limited rotation relative to said shaft, said assembly comprising two discs keyed together for simultaneous rotation upon the shaft and a third disc floatingly supported by the shaft and keyed for limited free rotation relative to said two discs, means for keying said disc assembly to said first-mentioned disc for limited free rotation relative to said first disc, figures simulating baseball players pivotally carried by one of said two discs and adapted for movement from and to a projected position

with respect to said one of said two discs, means for projecting said figures from said one of said two discs, and means adapted to engage the first-named disc and the other of the discs of said two discs at the completion of their rotation through a predetermined arc whereby to adjust said first-named disc and said disc assembly in a position with respect to each other whereby to position said figures in a predetermined position with respect to the shaft at the completion of rotation of said shaft through said predetermined arc.

4. An apparatus of the class described comprising a rotatable shaft, a disc fixed to said shaft for rotation therewith, a disc assembly on said shaft adapted for limited rotation relative to said shaft, said assembly comprising two discs keyed together for simultaneous rotation upon the shaft and a third disc floatingly supported by the shaft and keyed for limited free rotation relative to said first disc, figures simulating baseball players pivotally carried by one of said two discs and adapted for movement from and to a projected position with respect to said one of said two discs, means for projecting said figures from said one of said two discs, and means adapted to engage the first-named disc and the other of the discs of said two discs at the completion of their rotation through a predetermined arc whereby to adjust said first-named disc and said disc assembly in a position with respect to each other whereby to position said figures in a predetermined position with respect to the shaft at the completion of rotation of said shaft through said predetermined arc, said last-named means including a spring-urged detent, a V-shaped notch in said first-named disc, and a slot in said other of said two discs, said detent being adapted to engage in said notch and said slot.

HARRY E. WILLIAMS.
